UNITED STATES PATENT OFFICE

110,488

DESIGN FOR AN ADVERTISING SIGN

Charles V. Hike, Bellevue, Nebr.

Application April 1, 1938, Serial No. 76,212

Term of patent 3½ years

To all whom it may concern:

Be it known that I, Charles V. Hike, a citizen of the United States, residing at Bellevue, in the county of Sarpy and State of Nebraska, have invented a new, original, and ornamental Design for an Advertising Sign, of which the following is a specification, reference being had to the accompanying drawing, forming part thereof.

The figure is a plan view of an advertising sign showing my new design. The sign is of no appreciable thickness and the features thereof are flush with the surface.

I claim:

The ornamental design for an advertising sign as shown and described.

CHARLES V. HIKE.
